UNITED STATES PATENT OFFICE.

WARREN J. SUTLIFF, OF SCHENECTADY, NEW YORK.

JOURNAL-BOX.

1,092,306.

Specification of Letters Patent. Patented Apr. 7, 1914.

Application filed November 11, 1913. Serial No. 800,324.

To all whom it may concern:

Be it known that I, WARREN J. SUTLIFF, a citizen of the United States, residing at Schenectady, in the county of Schenectady and State of New York, have invented certain new and useful Improvements in Journal-Boxes, of which the following is a specification.

The present invention relates to improvements in journal-boxes, and is applied especially to the cellar of the driving box of a locomotive of the steam railroad type.

The object of the invention is to improve the construction of the cellar in relation to its driving box so that certain difficulties may be overcome and objectionable features eliminated in the driving box construction of locomotives in modern use.

In the process of assembling the parts of a locomotive driving box, the bearing is pressed into the box with a power of from twenty-five to thirty-five tons pressure before the ends of the box are slotted. This excessive pressure of course spreads or expands the box to a certain extent. After being slotted the box with its bearing is driven into the frame and the cellar is then applied. When the locomotive is first placed in service the parts of the bearing including the box and cellar are expanded due to heat, but after the journal has been running for some time the parts are smoothed and friction is reduced and consequently the heat. The parts now contract and the result is that the cellar is held so tightly in the box that much time and labor are consumed in withdrawing the cellar from the box, and frequently it becomes necessary to break the cellar before it can be removed from the box, which of course renders the cellar worthless for further use and requires the services of a new cellar. This operation is necessary with the renewal of the bearing brasses and many times the cellar and box are both ruined when dropping the wheels to furnish new brasses. By the utilization of my improved cellar these and other difficulties are removed as will be hereinafter pointed out.

In the accompanying drawings I have illustrated one complete example of the physical embodiment of my invention constructed according to the best mode I have so far devised for the practical application of the principles of my invention.

Figure 1 is a front elevation of a journal

box involving my invention. Fig. 2 is a side view, partly broken away showing the cellar in section. Fig. 3 is a perspective view of my improved cellar. Fig. 4 is a perspective view of a locking bar or key for the cellar. Fig. 5 is a view of one of the slotted studs for the locking key. Fig. 6 is a modified form of the cellar.

The invention is applicable for use with the standard driving box for locomotives now in use and the box is equipped with the invention by the addition of drilling two holes therein as will be described. The box 1, journal bearing or brass 2 and journal 3 are of usual type, and the box is fitted with 70 a pair of studs 4, 4, projecting from the front wall thereof near the bottom. These studs are tapped into holes that are drilled into the metal of the box, and are provided with a slot 5 for a cotter pin 6.

The cellar 7 is clearly shown in Fig. 3 where it is apparent that it has an open bottom and its front and rear walls are curved for the journal. On the front wall of the cellar are spaced two ribs 8 which are undercut on their adjoining faces to provide a dovetail groove therebetween which extends from side to side of the cellar. This groove is for the accommodation of the locking key 9 which is formed with beveled edges complementary to the dovetail groove, and the key also is slotted at 10, 10, to pass over the studs 4 and perforated at 11 to pass over a stud 12 fixed in the front of the cellar, and by means of which the key is held to the 60 cellar.

As illustrated in the drawings, the cellar is in two pieces, the bottom being formed of a base plate 12' having a rear upwardly projecting flange 13 to fit into a recess 14 in the cellar, and a pair of ribs 15, 15, extending across the bottom, and perforated for the two locking keys 16, 16 passed therethrough and through the perforated lugs 17, 17 of the box. As a safety device, after the parts are in place, the cellar and its bottom are held together by means of the bolt 18, which is passed through the perforated lugs 19, 20 on the cellar and bottom respectively.

In assembling the parts after the brass has been located and the box placed *in situ*, the base or bottom only of the cellar is now forced in between the ends of the box and the locking bars or keys 16 are located. The cellar is now ready to be placed, having pre-

viously had its locking key secured over the stud 12 in the dovetail groove, and the cellar is pushed into position under the journal. It will be understood that the cellar base 5 holds the box slightly distended, and the cellar is free to pass into the box, not only on account of this slight distention, but because it is purposely made of less dimensions and has a loose fit in the box. The slotted ends 10 of the key pass over the studs 4 and the cotters 6 prevent displacement of the key. As before stated the bolt 18 may now be secured in place.

Whenever it is necessary to remove the 15 brasses, the cellar is first removed by withdrawing the bolt 18 and cotters 6 and then bodily withdrawing the cellar. The two keys 16, are then removed and the space formerly occupied by the cellar provides an 20 opening for a jack by means of which the box is spread sufficiently to permit the withdrawal of the base of the cellar. The removal of the cellar permits access to the hub 25 face of the driving wheels so that they may be inspected at frequent intervals, and it will be apparent that the cellar can be removed as easily under the locomotive, as if it were entirely free therefrom.

In Fig. 6 I have illustrated a cellar 7' 30 having a closed bottom 7^a. This type of cellar is employed when liquid oil is used as the lubricant, and the type of box shown in Fig. 3, without the bottom, is usually em-

ployed when the lubricant is made up of grease.

From the above description taken in connection with my drawings it is evident that I have provided an improved cellar that will accomplish the purposes and objects of my invention in a comparatively perfect manner.

Having thus fully described my invention what I claim as new and desire to secure by Letters Patent is:—

1. The combination with a driving box, of a cellar having a pair of transversely extending horizontally undercut ribs, of a locking key having beveled edges to fit between said ribs and having its ends extended over the driving box, studs projecting from the driving box, said key having perforations to fit over said studs and means for locking the key on the studs.

2. The combination with a driving box, and a cellar having a pair of spaced retaining ribs, of a key dove tail in cross section 51 located between said ribs with its ends extending over the adjoining edges of the driving box, and means for securing said key to the driving box.

In testimony whereof I affix my signature in presence of two witnesses.

WARREN J. SUTLIFF.
